UNITED STATES PATENT OFFICE.

HENRY A. NETTLETON, OF MANCHESTER, CONNECTICUT.

TROLLEY-HEAD.

SPECIFICATION forming part of Letters Patent No. 668,453, dated February 19, 1901.

Application filed December 20, 1900. Serial No. 40,530. (No model.)

To all whom it may concern:

Be it known that I, HENRY A. NETTLETON, a citizen of the United States, residing at Manchester, in the county of Hartford and 5 State of Connecticut, have invented certain new and useful Improvements in Trolley-Heads, of which the following is a specification.

My invention relates to the class of devices 10 used for receiving a current of electricity from a wire or like means of supply and serving as a part of the means for conveying the fluid to a motor or like part arranged on a vehicle; and the object of my invention is to provide 15 a device of this class more especially designed for use on a trolley-pole by means of which the trolley-wheel may be readily attached to or removed from the trolley-pole.

A device in connection with which my invention is applicable is illustrated in the accompanying drawings, in which—

Figure 1 is a view in side elevation of a portion of a trolley-head supplied with my improved attaching means. Fig. 2 is a like 25 view showing the latch in its raised position. Fig. 3 is an edge view of the trolley-head supplied with my improved attaching means. Fig. 4 is a detail view of the trolley-wheel axle or spindle.

30 A difficulty has been experienced in devices of this class prior to my invention when it is desired to remove the trolley-wheel for any purpose from the trolley-head, prior devices of this class containing faults in construction whereby the trolley-wheel is not securely held in position or in which considerable labor is involved in removing or attaching the trolley-wheel. My invention provides a device in which all of these faults 35 of prior construction are done away with and by the use of which a trolley-wheel may be easily and readily removed or replaced.

In the accompanying drawings the letter *a* denotes a portion of a trolley-head that may 45 be attached to the trolley-pole after any of the well-known forms of construction. This head is preferably provided with an offset portion *a'* on each side part of the head, between which side parts the trolley-wheel *b* is 50 located, these offset portions providing depressions or recesses *a''*. Slots *a'''* extend from

the upper edge of each side part of the trolley-head for a short distance inward, the bottom of these slots forming a bearing for the trolley-wheel axle or spindle *c*. This spindle 55 *c* has at each end and on opposite sides thereof retaining-grooves *c'*, adapted to receive the edges of the side parts of the trolley-head appurtenant to the slots *a'''*. The head may be provided with the usual conducting-pieces *d*, 60 extending downward from the axle or spindle *c* into the hollow body part of the head. When these conductors are employed, the upper edges are provided with slots so arranged with respect to the slots *a'''* that the 65 axle may be inserted therein. These conductors preferably extend a short distance above the axle. Washers *e*, commonly used in this form of device, may also be employed, if desired, these washers being placed on the 70 axle, so that they will be removed or replaced therewith in the head.

A latch *f* is pivoted to the trolley-head in a manner to retain the axle or spindle *c* securely in place. In the preferred form of the invention and as shown herein this latch is 75 formed to U shape, each branch being located appurtenant to a side part of the trolley-head. The outer ends of each branch are bent at an angle to the opposite end of the branch, 80 and these ends are pivoted at *f'* to the side parts of the trolley-head. A recess *f''* is formed in the latch of a shape to receive the axle or spindle *c*. When the latch is in position to hold the axle in place, the latch lies, 85 preferably, wholly within the depressions or recesses *a''*, so that no projecting parts or uneven surfaces are presented to be caught upon a trolley-wire or the like.

The lower part or cross-bar, preferably, of 90 the latch is provided with a spring-catch *g*, suitably constructed and arranged to hold the latch securely in position.

In a device embodying my invention and constructed as herein illustrated and described I have provided means whereby the trolley-wheel and its spindle may be readily removed or replaced for any purpose; but I do not desire to limit myself to the precise construction herein set out, as it is obvious 95 that the details may be departed from to a considerable extent and even the essential 100

features altered without departing from the scope of the invention.

What I claim as my invention, and desire to secure by Letters Patent, is—

- 5 1. In a trolley-head, in combination, the side parts having slots for the reception of the trolley-wheel axle, the trolley-wheel axle supported in said slots and bearing a trolley-wheel, and a latch arranged to lie across the 10 slots to hold the axle in position.
- 15 2. In a trolley-head, in combination, forked side parts having slots for the reception of the trolley-wheel axle, the trolley-wheel axle supported in said slots and bearing a trolley-wheel, and a swinging latch pivoted to the 20 side parts of the trolley-head and arranged to project across the slots to hold the axle in position.
- 25 3. In a trolley-head, in combination, forked side parts having slots for the reception of the trolley-wheel axle, the trolley-wheel axle supported in said slots and bearing a trolley-wheel, and a latch pivoted to the side parts of the trolley-head and arranged to extend across the 30 slots to hold the trolley-wheel axle in position.
- 35 4. In a trolley-head, in combination with the forked side parts having slots for the reception of a trolley-wheel axle and recesses 30 on the inner surface of the side parts for the reception of a latch, a trolley-wheel axle located in said slots and bearing a trolley-wheel, and a latch pivoted to the side parts of the trolley-head and arranged to extend across

said slots to hold the trolley-wheel axle in 35 position.

5. In a trolley-head, in combination with the forked side parts having slots in the upper edge thereof for the reception of a trolley-wheel axle and recesses along the inner surface of the side parts for the reception of a latch, a trolley-wheel axle bearing a trolley-wheel and located in said slots, and a latch having branches pivoted to the side parts of the trolley-head and arranged to lie within 45 said recesses and also to project across said slots to hold the trolley-wheel axle in position, and means for holding the latch in its closed position.

6. In combination in a trolley-head, side 50 parts having slots for the reception of the trolley-wheel axle, conducting-pieces secured to the side parts and having slots for the reception of the trolley-wheel axle, the trolley-wheel axle arranged to be supported in said 55 slots, and a latch arranged to extend across a slot to hold the trolley-wheel axle in position.

7. In a trolley-head, in combination, side parts arranged to support a trolley-wheel axle, the trolley-wheel axle supported by said side 60 parts and bearing a trolley-wheel, and a latch arranged to extend across the axle to hold it in position.

HENRY A. NETTLETON.
